(57) **ABSTRACT**

The exemplary embodiments herein provide a lighting system for a display case having at least one edge. A lighting assembly is positioned along an edge of the display case or a door assembly, where a transparent or semi-transparent rod is positioned adjacent to the lighting assembly to act as a lens element. The rod is generally placed parallel to the edge of the display case or door assembly. The lighting assembly preferably includes a mounting structure which contains a substrate with a plurality of LEDs along with the rod. A blinder may extend rearwardly from the mounting structure to prevent headlighting.

FIG. 1

FIG. 3

FIG. 4

ROD AS A LENS ELEMENT FOR LIGHT EMITTING DIODES

CROSS-REFERENCE TO RELATED APPLICATIONS

This application claims priority to U.S. application Ser. No. 61/980,876 filed on Apr. 17, 2014 which is herein incorporated by reference in its entirety.

TECHNICAL FIELD

Embodiments generally relate to the use of a transparent or semi-transparent rod as a lens element for LEDs.

BACKGROUND OF THE ART

Display cases are used in a number of different retail establishments for illustrating the products that are available for sale. In some instances, these display cases may be coolers or freezers which are placed in grocery stores, convenience stores, gas stations, restaurants, or other retail establishments. In other instances, these display cases may be non-refrigerated transparent containers used in a jewelry or watch store, bakery, deli, antique shop, sporting goods store, electronics store, or other retail establishments. The lighting within these cases can be important to the way in which the product is presented to the consumer.

It has now become desirable to utilize the transparent glass that is typically placed in display cases with additional POS advertising. Most notably, it has been considered that transparent LCDs may be positioned along with the transparent glass and could display additional advertising materials while still allowing a patron to view the products inside the display case. In this way, the lighting is further important to the impression of the consumer, not only for the appearance of the products on the shelves, but also for the appearance of the transparent LCD.

SUMMARY OF THE EXEMPLARY EMBODIMENTS

Exemplary embodiments utilize a plurality of LEDs positioned along one or more edges of a display case where a rod lens element is positioned along the plurality of LEDs.

The foregoing and other features and advantages of the present invention will be apparent from the following more detailed description of the particular embodiments, as illustrated in the accompanying drawings.

BRIEF DESCRIPTION OF THE DRAWINGS

A better understanding of an exemplary embodiment will be obtained from a reading of the following detailed description and the accompanying drawings wherein identical reference characters refer to identical parts and in which:

FIG. 1 is a front perspective view of an exemplary embodiment of the lighting system used within a display case and indicating the horizontal section line A-A.

FIG. 2 is a top perspective section view taken along the section line A-A and indicating Detail 3.

FIG. 3 is a detailed perspective section view of Detail 3 shown in FIG. 2.

FIG. 4 is a top planar section view of Detail 3 shown in FIG. 2.

FIG. 5 is a top planar section view taken along the section line A-A where only the door assembly is shown and Details A, B, and C are indicated.

FIG. 6 is a top planar section view of Detail A, indicated in FIG. 5.

FIG. 7 is a top planar section view of Detail B, indicated in FIG. 5.

FIG. 8 is a top planar section view of Detail C, indicated in FIG. 5.

10

DETAILED DESCRIPTION

The invention is described more fully hereinafter with reference to the accompanying drawings, in which exemplary embodiments of the invention are shown. This invention may, however, be embodied in many different forms and should not be construed as limited to the exemplary embodiments set forth herein. Rather, these embodiments are provided so that this disclosure will be thorough and complete, 15 and will fully convey the scope of the invention to those skilled in the art. In the drawings, the size and relative sizes of layers and regions may be exaggerated for clarity.

The terminology used herein is for the purpose of describing particular embodiments only and is not intended to be 20 limiting of the invention. As used herein, the singular forms “a”, “an” and “the” are intended to include the plural forms as well, unless the context clearly indicates otherwise. It will be further understood that the terms “comprises” and/or “comprising,” when used in this specification, specify the 25 presence of stated features, integers, steps, operations, elements, and/or components, but do not preclude the presence or addition of one or more other features, integers, steps, operations, elements, components, and/or groups thereof.

Embodiments of the invention are described herein with 30 reference to illustrations that are schematic illustrations of idealized embodiments (and intermediate structures) of the invention. As such, variations from the shapes of the illustrations as a result, for example, of manufacturing techniques and/or tolerances, are to be expected. Thus, embodiments of the invention should not be construed as limited to the particular shapes of regions illustrated herein but are to 35 include deviations in shapes that result, for example, from manufacturing.

Unless otherwise defined, all terms (including technical 40 and scientific terms) used herein have the same meaning as commonly understood by one of ordinary skill in the art to which this invention belongs. It will be further understood that terms, such as those defined in commonly used dictionaries, should be interpreted as having a meaning that is consistent with their meaning in the context of the relevant art and will not be interpreted in an idealized or overly formal sense unless expressly so defined herein.

FIG. 1 is a front perspective view of an exemplary embodiment of the lighting system used within a traditional 45 display case 100 and indicating the horizontal section line 2-2. Typically, a display case 100 contains a five sided housing 35 with a door assembly 49 attached to enclose the products within the display case 100. Here, the door assembly 49 contains two opposing vertical edges 50 and 55 which 50 contain the exemplary lighting assembly. However, it should be noted that lighting assemblies can also be placed along the two opposing horizontal edges 52 and 53. It is also possible to place the lighting assemblies only along the two edges 52 and 53. It is further possible to place the lighting 55 assembly only along one of the edges 50, 52, 53, or 55. Generally, it has been found that exemplary embodiments would place the lighting assemblies along the longest of the

two pairs of edges, which can vary depending upon the orientation of the front of the display case.

Of course, in this embodiment the front of the case 100 contains the door assembly 49, but in many other embodiments the case 100 simply contains a front glass assembly, without being an actual door that hinges to provide access to the interior of the case 100. The electronics 25 for driving the lighting assembly are shown within a bottom compartment of the display case 100, but the electronics could be placed anywhere, so long as they provide electrical communication to the lighting assemblies.

FIG. 2 is a top perspective section view taken along the section line 2-2 and indicating an area of detail shown in enlarged form in FIG. 3. Here, a first lighting assembly 130 is shown positioned along the edge 50, while a second lighting assembly 125 is positioned along the edge 55.

FIG. 3 is an enlarged view of the area indicated as FIG. 3 in FIG. 2. The door assembly 49 contains a rear glass 84, liquid crystal layer 82, and a front glass 80 which are held between the two edges 50 and 55. The lighting assembly 130 is attached to a portion of the edge 50 which faces the interior of the display case 100. In this embodiment of the lighting assembly 130, a mounting structure 275 is attached to the edge 50 and contains both the LEDs 200 as well as the rod lens element 250. A blinder 230 preferably extends from the mounting structure 275 and prevents headlighting (a concept that will be discussed further below).

FIG. 4 is an enlarged top planar view of the area indicated as FIG. 3 in FIG. 2. Generally speaking, the mounting structure preferably contains an arm 276 which extends rearward to define a U-shaped channel to contain the rod lens element 250 and LEDs 200. The mounting structure 275 and its associated arm 276 preferably define a slot 300 which is sized to accept the PCB 210 containing the LEDs 200. A rod lens element 250 may then be sandwiched between a rear ledge 290, front ledge 280, and the LEDs 200. In an exemplary embodiment, the mounting structure 275 may be extruded or injection molded and the PCB 210 may slide into the end of the extruded or molded structure. The rod lens element 250 can then be snapped into place by forcing the rear ledge 290 away from the front ledge 280 enough to insert the rod lens element 250. The mounting structure 275 is preferably plastic and more preferably a PVC, but could also be an extruded metal such as aluminum. The rod lens element 250 is a transparent or semi-transparent material which could be acrylic or glass.

It is preferable that the diameter of the rod lens element 250 is slightly larger than the width of the LED 200. For example, if the LED chip is 5 mm×5 mm, it has been found that rod diameters equal to or larger than 5 mm are preferred. Specifically, it is preferable that the rod diameter is one millimeter larger than the LED chip, and is then centered over the LED chip. In a preferred embodiment, the LED chip is 5 mm×5 mm and the diameter of the rod lens element is 6 mm. As shown in the figures, the central axis of the rod (here going into/out of the page) runs parallel to the strip of LEDs 200.

Generally, the central axis 202 of the LED 200 should be approximately 4-8 degrees from parallel with the rear glass 84 (which should be substantially parallel to the LCD 82, and front glass 80). In an exemplary embodiment, the central axis 202 of the LED 200 should be approximately 5-7 degrees from parallel with the rear glass 84. Also preferably the blinder 230 will extend rearward to a point almost equal to the rear-most point of the LED 200. Generally speaking,

the angle of the central axis 202 and the length of the blinder 230 should be tailored to prevent headlighting, which will be discussed further below.

FIG. 5 is a top view of only the sectioned door assembly 49 of FIG. 2, where areas of detail shown in enlarged form in FIGS. 6-8 are indicated. Here, the headlighting from the lighting assembly placed along the edge 55 is analyzed. Headlighting, as used in this application, is the phenomenon of direct paths of LED light passing through the rear glass, 10 LCD, and front glass to impact the eye of an observer outside of the display case.

FIG. 6 is an enlarged top planar view of the area indicated as FIG. 6 in FIG. 5. In this figure, the line 500 represents the visual line starting from the most rearward point of the rod lens element 250, passing by the blinder 230, and refracting through the rear glass, LCD, and front glass. As noted above, the angle of the axis of the LED as well as the length of the blinder 230 should be selected so that line 500 would be approximately at the outside corner 51 of the door assembly 49 (or simply the front glass assembly if not using an opening/closing door) so that it would not be directly visible by an observer. Thus, even at the most extreme angles, light exiting the lens 250 would not be directly visible to an observer, as this light would be caught by the edge 50 with almost all of the light being directed back into the case 100, only to be reflected off the contents and back through the LCD and front glass.

FIG. 7 is an enlarged top planar view of the area indicated as FIG. 7 in FIG. 5.

FIG. 8 is an enlarged top planar view of the area indicated as FIG. 8 in FIG. 5.

Having shown and described a preferred embodiment of the invention, those skilled in the art will realize that many variations and modifications may be made to affect the 35 described invention and still be within the scope of the claimed invention. Additionally, many of the elements indicated above may be altered or replaced by different elements which will provide the same result and fall within the spirit of the claimed invention. It is the intention, therefore, to 40 limit the invention only as indicated by the scope of the claims.

We claim:

1. A lighting system for a display case comprising:
a door glass assembly having a front glass located to front the environment in which the display case will be situated, a rear glass located rearward of the front glass, and at least one edge;
a lighting assembly placed along the at least one edge of the door glass assembly and rearward of the rear glass, the lighting assembly comprising a mounting structure including a U-shaped channel that defines a slot and a PCB with a plurality of LEDs mounted thereto located within the slot, the lighting assembly oriented such that forward-angled light rays emitted by the lighting assembly will be refracted by the rear glass toward the front glass;
a transparent rod placed adjacent to the lighting assembly and in the path of the light rays emitted by the lighting assembly; and
a blinder which extends rearwardly from the mounting structure;
wherein the length of the blinder and the angle of the LEDs relative to the rear glass is such that the forward-angled light emitted by the LEDs will strike the door glass assembly at an outside corner thereof to prevent a direct view of a light source of the lighting assembly

5

through the door glass assembly when the lighting system is installed to the display case.

2. The lighting system of claim 1 wherein:
the rod contains a central axis that is substantially parallel to the at least one edge of the door glass assembly. 5
3. The lighting system of claim 1 wherein:
the rod is located within the U-shaped channel.
4. The lighting system of claim 1 wherein:
the mounting structure defines a front and rear ledge which sandwich two sides of the rod. 10
5. The lighting system of claim 1 wherein:
the rod is comprised of a material selected from the group consisting of acrylic and glass.
6. The lighting system of claim 1 further comprising:
a layer of liquid crystal material placed in between the 15 front glass and the rear glass.
7. The lighting system of claim 1 wherein:
a central axis of each LED is positioned between 4 and 8 degrees of parallel with the front glass. 20
8. The lighting system of claim 1 wherein:
a central axis of the rod is substantially parallel with a central axis of the PCB having the plurality of LEDs.
9. A lighting system for a display case comprising:
a door assembly having a front glass located to front the environment in which the display case will be situated, 25 a rear glass located rearward of the front glass and adjacent an interior space of the display case, a layer of

6

liquid crystal material located between the front and rear glass, and at least one edge;
a mounting structure positioned along the at least one edge and having a U-shaped channel with a slot positioned near a bottom of the U-shaped channel and rearward of the rear glass;
a substrate containing a plurality of LEDs positioned within the slot, the slot oriented such that forward-angled light rays emitted by the LEDs will be refracted by the rear glass toward the front glass;
a front ledge and a rear ledge defined by the mounting structure; and
a transparent rod positioned within the U-shaped channel and contacting the front ledge, rear ledge, and the plurality of LEDs.

10. The lighting system of claim 9 wherein:
the mounting structure further includes a blinder that extends rearwardly therefrom; and
the length of the blinder and the angle of the LEDs relative to the rear glass is such that the forward-angled light from the LEDs will strike the door assembly at an outside corner thereof.
11. The lighting system of claim 10 wherein:
a central axis of the plurality of LEDs is positioned between 4 and 8 degrees of parallel with the front glass.
